AMPLIFYING SYSTEM

James L. Potter, New Brunswick, N. J., assignor
to General Electric Company, a corporation of
New York

Application May 22, 1941, Serial No. 394,572

2 Claims. (Cl. 179—171)

My invention relates to an amplifying system and particularly to a multi-stage amplifying system of the feed-back type.

In certain applications of signal amplifiers, it is desirable to have the voltage gain through the amplifier substantially independent of variations in the impedance of a load device coupled to its output. For example, a class B amplifier, i. e., one in which anode current flows in the individual tubes only during half cycles of the applied voltage, presents a load impedance to the driving source which varies appreciably over each cycle due to the varying grid currents drawn during portions of each cycle. Therefore, if the proper grid excitation is to be supplied to its input, it is necessary for the driver stage to have low internal impedance. For perfect voltage regulation of the driver stage under these conditions, its apparent internal impedance should be exactly equal to zero. If such is the case, the output voltage of the driver stage will always be proportional to the input voltage regardless of the value of its external load impedance.

An approach has been made to these conditions by employing a driver amplifier of considerable power output, and in some cases by loading the secondary of the output transformer with a relatively low resistance comparable to the minimum grid impedance of the class B amplifier. This loading resistance necessarily absorbs a considerable amount of power which is not effective in driving the grids of the class B amplifier.

In order to decrease the apparent internal resistance of the driver stage without sacrificing efficiency of operation, it has been proposed to use feedback in the driver amplifier. In accordance with the present invention, a combination of positive and negative feedbacks is utilized in a multi-stage amplifier for the attainment of this result. Briefly, in a preferred embodiment of my invention, a particular form of impedance network is interconnected with two cascaded amplifying stages. This network functions to provide a degenerative feedback between the grid and anode circuits of each stage controlled by its own anode current, and a regenerative feedback between the stages which is controlled by the anode current in the second stage. By a proper design of the circuit elements the apparent anode resistance to the second stage may be made as low as desired. It may be reduced substantially to zero, or even made negative, as will appear more fully hereinafter.

It is therefore a primary object of my invention to provide an improved multi-stage feed-back amplifier which is particularly adapted to supply power to a variable impedance load device.

Another object of my invention is to provide a simple and efficient feedback amplifier in which the apparent anode impedance of the output stage may be given a desired value differing materially from its actual resistance.

A further object of my invention is to provide an improved amplifier of this general type wherein the apparent anode impedance of the output stage may be made substantially equal to zero, and the voltage gain through the amplifier thereby made independent of variations in the output load impedance.

Still another object of my invention is to provide an improved multi-stage amplifier which has a combination of positive and negative feedbacks and which is stable in operation and readily adjusted.

It is also specifically an object of my invention to provide an improved multi-stage amplifier of the positive-negative feedback type which has particular utility as a driver amplifier for a class B amplifier or the like.

The features of my invention which I believe to be novel are set forth with particularity in the appended claims. My invention itself, however, together with further objects and advantages thereof, may best be understood by reference to the following description taken in connection with the accompanying drawing, in which Fig. 1 diagrammatically represents a class B push-pull amplifier with a two-stage driver amplifier embodying my invention; and Figs. 2—5 are curves representative of the operating characteristics of a particular experimental amplifying system embodying my invention.

In the amplifying system represented in Fig. 1, signal voltages from a suitable source, not shown, are impressed upon the primary winding of the input transformer 10. For example in an audio system, these voltages may be audio frequency signals. The secondary winding of the transformer 10 is coupled to the input of a voltage amplifier having two stages 11 and 12. The amplified signal voltages are supplied from the output of this amplifier to the input circuit of a push-pull class B amplifier 13 through a coupling transformer 14. The output of the amplifier 13 is supplied to any suitable utilization device, not shown, through the output coupling transformer 15. For example, the output of the

amplifier 13 may be supplied to a sound reproducer, or the amplifier 13 may be used as a class B modulator for a radio transmitter.

The first stage 11 comprises an electron discharge amplifier T_1 which is illustrated as a triode having a cathode 16, control grid 17, and anode 18. Signal voltages e_s are impressed between the grid 17 and ground from the secondary of the input transformer 10. Cathode 16 is connected to ground through two resistors R_1 and R_3 in series. The anode 18 is connected to ground through a coupling resistor R_0 and a suitable source of anode operating potential, represented conventionally by a battery 19.

Signal voltages appearing on the anode 18 are supplied to the input circuit of the second stage 12 through a coupling capacitor 20. The stage 12 comprises a second electron discharge amplifier T_2 , which is represented as a pentode having a cathode 21, control grid 22, screen grid 23, suppressor grid 24 and anode 25. In the particular system illustrated, the suppressor grid 24 is internally connected to the cathode 21 in the usual manner and the screen grid 23 is connected to the anode 25 so that the device T_2 effectively functions as a triode amplifier. A grid resistor 26 is connected from the junction of the coupling capacitor 20 and the control grid 22 to ground. The cathode 21 is connected to ground through a resistor R_2 and the previously-mentioned resistor R_3 . The anode 25 and screen grid 23 are connected to ground through the primary winding of the output transformer 14 and the potential source 19. The output voltage e_o is impressed upon the transformer 14.

As shown at Fig. 1, the push-pull amplifier 13 comprises two duplex triodes T_3 and T_4 connected in parallel, on one side of the amplifier, and similar duplex triodes T_5 and T_6 connected in parallel, on the other side. It will, of course, be apparent to those skilled in the art that by using a plurality of amplifiers connected in parallel increased power output may be supplied from the transformer 15. The grids of these amplifiers

are biased approximately to cutoff for class B operation from a suitable bias source, represented conventionally by the battery 27. Suitable anode

operating potentials are supplied from a high potential source, represented by the battery 28.

Considering now particularly the driver am-

plifier 11, 12 of Fig. 1, it will be observed that the common cathode circuits of the devices T_1 and T_2 are interconnected by means of the network comprising the three Y-connected resistors

will further be observed that the resistor R_3 is common to the grid and anode circuits of both amplifiers T_1 and T_2 . Therefore, a voltage is fed back to the grid circuit of T_1 which is proportional to the anode current in T_2 . This voltage is regenerative and tends to increase the gain of the amplifier.

By adjusting the values of the various resistors, the apparent anode impedance of the amplifier 10 T_2 may be given various desired values. If the positive and negative feedbacks are properly proportioned, the effective internal impedance of the amplifier T_2 can be made just equal to zero. Under these conditions the gain through the amplifier 11, 12 will be independent of the effective load impedance seen looking into the terminals of the primary winding of the transformer 14.

An exact analysis of this system is complicated, since all tubes are non-linear devices. However, by making the assumption that the tubes T_1 and T_2 behave as linear impedances over their operating ranges, a close approximation may be made. First solving for i_{p1} , the anode current of the tube T_1 , and considering the second tube T_2 and all feedback effects,

$$i_{p1} = \frac{\mu_1 e_s + \mu_1 R_3 i_{p2}}{R_{p1} + R_0 + (R_1 + R_3)(\mu_1 + 1)} \quad (1)$$

where

μ_1 =the amplification factor of T_1
 i_{p2} =the anode current of T_2 , and
 R_{p1} =anode resistance of T_1

Likewise, solving for i_{p2} , the anode current of the second tube T_2 ,

$$i_{p2} = \frac{\mu_2 R_0 i_{p1}}{R_{p2} + Z_0 + (R_2 + R_3)(\mu_2 + 1)} \quad (2)$$

where

μ_2 =the amplification factor of T_2 , and
 Z_0 =the output load impedance seen looking into the primary winding of transformer 14.

Equations 1 and 2 may now be solved in terms of i_{p2} , eliminating i_{p1} , from which it follows that

$$i_{p2} = \frac{\mu_1 \mu_2 R_0 e_s}{[R_{p2} + Z_0 + (R_2 + R_3)(\mu_2 + 1)][R_{p1} + R_0 + (R_1 + R_3)(\mu_1 + 1)] - \mu_1 \mu_2 R_0 R_3} \quad (3)$$

Since the gain of the amplifier is equal to the quotient of e_o divided by e_s ,

Gain=

$$\frac{\mu_1 \mu_2 R_0 Z_0}{[R_{p2} + Z_0 + (R_2 + R_3)(\mu_2 + 1)][R_{p1} + R_0 + (R_1 + R_3)(\mu_1 + 1)] - \mu_1 \mu_2 R_0 R_3} \quad (4)$$

Equation 4 may also be written in the following form:

Gain=

$$\frac{\mu_1 \mu_2 R_0 Z_0}{[R_{p2} + Z_0 + (R_2 + R_3)(\mu_2 + 1)][R_{p1} + R_0 + (R_1 + R_3)(\mu_1 + 1)] - \mu_1 \mu_2 R_0 R_3} \quad (5)$$

If the amplifier T_2 is to appear as though it had zero anode impedance, thereby making the gain of the amplifier independent of the load impedance Z_0 , then

$$[R_{p2} + (R_2 + R_3)(\mu_2 + 1)][R_{p1} + R_0 + (R_1 + R_3)(\mu_1 + 1)] = \mu_1 \mu_2 R_0 R_3 \quad (6)$$

65 Solving for R_3 :

$$R_3 = \frac{[R_{p2} + (R_2 + R_3)(\mu_2 + 1)][R_{p1} + R_0 + (R_1 + R_3)(\mu_1 + 1)]}{\mu_1 \mu_2 R_0} \quad (7)$$

70 The quantities of $(R_1 + R_3)$ and $(R_2 + R_3)$ are the required bias resistances for each amplifier. Hence, their value is known for any given types of tubes. However, it must be taken into consideration that the anode current of both amplifiers flow through the resistance R_3 . Therefore, in

R_1 , R_2 and R_3 . It will further be apparent that the anode current for the amplifier T_1 must flow through the resistors R_1 and R_3 . Since the resistors R_1 and R_3 are unbypassed, this provides a degenerative feedback to the grid 17 which is proportional to the anode current in tube T_1 and substantially uniform at all signal frequencies in the operating range. Similarly, the flow of anode current in the device T_2 through the resistors R_2 and R_3 provides a uniform current-controlled degenerative feedback to its control grid 22. It

general, Equation 7 must be solved by successive approximation.

When the amplifier is designed according to Equation 7, the total gain is expressed by the following:

Gain =

$$\frac{\mu_1 \mu_2 R_0}{R_{p1} + R_0 + (R_1 + R_3)(\mu_1 + 1)} \quad (8)$$

It follows from Equation 8 that the gain of the amplifier is now independent of the magnitude and phase angle of Z_0 .

It may further be noted that the gain of the amplifier 11, 12 without feedback is expressed by the following:

Gain =

$$\frac{\mu_1 \mu_2 R_0 Z_0}{(R_{p1} + R_0)(R_{p2} + Z_0)} \quad (9)$$

The gain with feedback may be made the same as the gain without feedback if the denominator of Equation 9 is made equal to the denominator of Equation 4.

Since the gain of the amplifier is independent of the magnitude of Z_0 when the circuit constants are proportioned in accordance with Equation 7, it can be seen that an amplifier designed in this manner is especially suited for working into a non-linear impedance, such as the grids of the class B amplifier 13 in the illustrated embodiment. Furthermore, since the gain is independent of the phase angle of Z_0 , this type of amplifier is also advantageous when working into an impedance which varies with frequency, because it tends to flatten the frequency response.

By making the anode impedance of the driver amplifier T_2 in Fig. 1 appear nearly equal to zero, a reduction in harmonic distortion in the class B amplifier 13 is also secured. It may even be found desirable in some cases to make the anode impedance of the driver T_2 appear somewhat negative so that an actual rise in voltage is obtained when the grids of the class B amplifier 13 are at maximum positive values. This will tend to compensate for the curvature generally occurring in the plate characteristic in this region and, also, to compensate for the losses in the coupling transformer 14.

In a particular apparatus embodying my invention, a type 6L7 tube was used for the amplifier T_1 , a triode-connected type 6F6 tube for the amplifier T_2 and type 6N7 tubes for the amplifiers T_3 — T_6 . The curves of Fig. 2 are actual test curves taken with this apparatus showing the harmonic content at the output transformer 15 plotted against the feedback resistance R_3 , which controls the current regeneration between the stages 11 and 12. The power output from the amplifier 13 was held constant at about 33.2 watts. In this particular instance the apparent anode impedance of the amplifier T_1 was equal to zero when the feedback resistance R_3 had a value of about 45 ohms. For values of R_3 above 45 ohms, the apparent anode resistance was negative and below 45 ohms, positive.

Fig. 3 shows experimental curves for this same apparatus, with R_3 equal to about 45 ohms, and illustrates the variation in anode current I_p and grid current I_g for the amplifier 16 plotted against signal volts input to the first stage 11 of the driver amplifier. Figs. 4 and 5 show the

corresponding variations in harmonic content and power output.

In this particular apparatus, the driver tube T_2 was working at maximum output. The harmonic distortion could have been reduced still further by utilizing a driver tube of greater capacity.

It will thus be apparent that an amplifying system embodying my invention has low harmonic distortion, high efficiency, is stable in operation and is easy to adjust. While I have shown a particular embodiment of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. In a signal amplifying system, first and second thermionic amplifiers, means for coupling said amplifiers in cascade relation comprising a coupling resistance R_0 , said amplifiers having internal anode resistances R_{p1} and R_{p2} respectively and amplification factors μ_1 and μ_2 respectively, degenerative feedback resistances R_1 and R_2 common to the grid and anode circuits of the respective amplifiers, and a regenerative feedback resistance R_3 common to the grid and anode circuits of both amplifiers, said resistances having values determined substantially by the relation:

$$R_3 = \frac{[R_{p1} + R_0 + (R_1 + R_3)(\mu_1 + 1)][R_{p2} + (R_2 + R_3)(\mu_2 + 1)]}{\mu_1 \mu_2 R_0}$$

whereby the gain through said amplifiers is substantially independent of the value of output load impedance in the anode circuit of said second amplifier.

2. In a driver amplifier for a class B amplifier or the like, the combination comprising first and second thermionic amplifying devices T_1 and T_2 each having an anode, cathode and control grid, said devices having internal anode resistances R_{p1} and R_{p2} respectively and amplification factors μ_1 and μ_2 respectively, resistance coupling means between said devices comprising a load resistor R_0 for T_1 , a degenerative-regenerative feedback network in said amplifier comprising three resistors R_1 , R_2 and R_3 connected in a Y, the free terminals of R_1 and R_2 being connected to the cathodes of T_1 and T_2 respectively and the free terminal of R_3 being connected to a point of reference potential, connections from the grids of T_1 and T_2 to said point through respective grid coupling impedances, a connection from the anode of T_1 to said point through R_0 , a connection from the anode of T_2 to said point through an output load impedance, and means for supplying anode operating potentials to said devices, said resistors being proportioned substantially in accordance with the relation:

$$R_3 = \frac{[R_{p1} + R_0 + (R_1 + R_3)(\mu_1 + 1)][R_{p2} + (R_2 + R_3)(\mu_2 + 1)]}{\mu_1 \mu_2 R_0}$$

whereby the apparent anode impedance of T_2 is substantially equal to zero.

JAMES L. POTTER.
